UNITED STATES PATENT OFFICE.

EDGAR W. PERRY, OF GEORGETOWN, SOUTH CAROLINA.

WHEEL-HUB.

1,072,983.

Specification of Letters Patent.

Patented Sept. 9, 1913.

Application filed November 16, 1912. Serial No. 731,759.

To all whom it may concern:

Be it known that I, EDGAR W. PERRY, a citizen of the United States, residing at Georgetown, in the county of Georgetown and State of South Carolina, have invented new and useful Improvements in Wheel-Hubs, of which the following is a specification.

The general object of the invention is to improve the construction of spring wheels shown in my co-pending application Number 628,504, filed May 20, 1911. And to this end the invention consists in constructions for permitting angular movement of the relatively movable parts of the wheel and means for cushioning such angular movement.

Other objects will appear and be better understood from that embodiment of my invention of which the following is a specification, reference being had to the accompanying drawings forming part hereof, in which:—

Figure 1 is a view partly in section and elevation of the hub portion of the wheel. Fig. 2 is a cross section on the line 2—2 of Fig. 1. Fig. 3 is a detail elevation of the guide. Fig. 4 is a detail perspective of one element of the cushioning device.

30 The spokes 5 are arranged in a circular portion 6. In the present instance, helical compression springs 7—7 are interposed between the circular portion 6 and the sleeve 8 their ends being arranged in depressions 9 in the sleeve and depressions 10 in the circular portion 6.

The guide members 11 and 12 are screwed onto the opposite end portions of the sleeve 8 and the radial arms 13 of these guide 40 members bear on the sides of the circular portions 6, while the circular portions of the guide members with which the arms are formed integral, cover the circular space surrounded by the member 6 all of which is 45 shown in Figs. 1 and 2.

In either side of the circular member 6 and between the adjacent sides of adjacent arms 13, are formed a pair of pits 14 and 15 and located in these pits are helical compression springs 16. Between the adjacent ends of the pits are arranged stop blocks 17 and arranged over the pits are plates 18 having lugs 19 which project into the pits and bear on one end of the springs. The 55 lugs of adjacent plates are located adjacent

to the remote ends of the plates while the adjacent ends of the plates are normally spaced from the stop blocks 17, as shown in Fig. 1. The remote ends of the plates bear on adjacent sides of the arms 13—13 so that 60 when the circular member 6 is moved relatively to the member 11 and in one direction, certain of the lugs will effect the compression of certain of the springs, while the other lugs will effect the compression of 65 the springs when the said circular member is moved in the opposite direction and relatively to the guide member 11.

Now inasmuch as the circular member is supported or rests upon the springs 7, the 70 wheel and axle are permitted to move relatively to each other, such relative movement being in a direction perpendicular to the axle, and since a space exists between the adjacent ends of the plates 18 and the 75 stop blocks 17 an amount of angular movement by the circular member 6 is permitted within the limits of this space. But such angular movement on the part of the circular member 6 will always be against the action of the springs 16 which, of course, will operate to absorb the jolt or jar which the 80 wheel receives, to effect such angular movement.

The guide members 11—11 are provided 85 with screw threaded bosses 20—20 onto the inner of which is screwed a cap 21 which is adapted to coöperate with a washer 22 to form a race for bearing balls 23. A nut 24 screwed onto the outer end of the axle 25 90 prevents displacement of the wheel and is adapted to coöperate with a cap 26 screwed onto the outer boss 20, to provide a race for the bearing balls 27.

For preventing displacement of the parts 95 I employ the rings 28—28 which are arranged over the opposite sides of the circular member 6 and retained by suitable fastening devices such as bolts 29, which pass through the said rings, stop blocks and 100 spokes.

What is claimed as new is:

A wheel hub comprising a sleeve, a circular member surrounding the sleeve, springs interposed between the circular member and 105 sleeve and having lateral sockets, guide members screwed onto the opposite end portions of the sleeve and having radial arms bearing on the sides of the circular member, springs arranged in the lateral sockets of 110

the circular member, plates having portions bearing on one end of the springs and arranged so as to have their adjacent ends in spaced relation and their remote ends bearing on adjacent sides of the arms of the guide members, stop blocks interposed between the adjacent ends of said plates, and rings secured to the spokes of the wheel and

arranged for preventing displacement of said plates.

10

In testimony whereof I affix my signature in presence of two witnesses.

EDGAR W. PERRY.
